UNITED STATES PATENT OFFICE.

JOHN L. WEBSTER, OF BROCKPORT, NEW YORK, ASSIGNOR OF ONE-HALF TO JOHN H. WELCH, OF BROCKPORT, NEW YORK.

EGG TRAY AND CARRIER.

1,149,103.

Specification of Letters Patent. Patented Aug. 3, 1915.

Application filed June 1, 1912, Serial No. 700,974. Renewed March 2, 1915. Serial No. 11,577.

To all whom it may concern:

Be it known that I, JOHN L. WEBSTER, a citizen of the United States, residing at Brockport, in the county of Monroe and State of New York, have invented new and useful Improvements in Egg Trays and Carriers, of which the following is a specification.

The present invention provides an article primarily intended for handling eggs, thereby preventing breakage both by the merchant and the consumer, with the result that loss attributable to this cause is minimized.

The invention contemplates a tray having sides of rigid material, a yieldable bottom of textile material cells formed by cords which are interlaced, a cover of peculiar formation for retaining the eggs in the tray, and a combined bail and fastener which is arranged so as to fold and be out of the way and at the same time engage the cover and retain it in proper position.

The invention consists of the novel features, details of construction and combination of parts, which hereinafter will be more particularly set forth, illustrated in the accompanying drawings, and pointed out in the appended claims.

Referring to the drawings, forming a part of the specification, Figure 1 is a perspective view of a combined egg tray and carrier embodying the invention. Fig. 2 is a transverse section on the line $x-x$ of Fig. 1. Fig. 3 is a longitudinal section on the line $y-y$ of Fig. 1. Fig. 4 is a horizontal section on the line $z-z$ of Fig. 1. Fig. 5 is a detail view of a portion of the cover. Fig. 6 is a sectional detail of an end portion of the cover on the line $w-w$ of Fig. 5.

Corresponding and like parts are referred to in the following description, and indicated in all the views of the drawings, by the same reference characters.

While the device may be provided in various sizes it is preferred to construct the same of such a size as to hold one dozen eggs.

The tray is of rectangular shape and its sides are formed of rigid material. The bottom 1 of the tray consists of textile which is secured to the tray in any manner. Strips 2 underlap the bottom 1 and are secured to the tray and serve to hold the bottom elevated, thereby preventing injury to the eggs placed in the tray. The pockets or cells for

receiving the eggs and holding them separated are formed by cords 3 which are located in longitudinal and transverse position and which are interlaced and secured at their ends in any manner to the sides of the tray. 60 Any number of cords may be employed as may be found most advantageous according to the size of the tray. Usually two sets of cords are sufficient, particularly for trays of a size intended to hold a dozen eggs. The 65 outermost cords are located adjacent the inner sides of the walls of the tray so as to prevent breakage of the eggs by striking the sides of the tray.

In the construction illustrated the sides of 70 the tray 4 have grooves 5 in their outer faces and these grooves are of a depth to receive the portions of the cords appearing on the outer side of the tray. Openings 6 are formed in the sides of the tray in the plane 75 of the grooves 5 and the cords 3 pass through such openings and cross from one set of openings to the next openings on the outer side of the tray. The cords do not project beyond the outer faces of the tray, 80 since the portions exterior to the tray are received in the grooves 5 in the manner stated and as clearly illustrated in the several views of the drawings. A cord of suitable size is passed backward and forward 85 in a zigzag direction through the openings formed in opposite sides of the tray, the ends of the cord being secured by means of pegs 5^a driven into the openings receiving the extremities of the cord. The textile bot- 90 tom is tacked or otherwise secured to the lower edges of the sides of the tray and is reinforced by the strips 2 which are fastened at their ends to the edge portions of the sides of the tray. 95

The cover 7 is constructed of sheet material pressed into shape, the preferable material being stout paper or pressed board. The blank from which the cover is formed comprises parallel ribs and depressions arranged to alternate, the depressions being arranged to come over the cord partitions and the ridges arranged in line with the cells so as to receive the upper ends of the eggs. Edge portions of the blank are 100 formed with inner cuts and the portions bordering upon such cuts are caused to overlap, as shown at 8, being secured by glue or other similar adhesive. Strips 9 are pasted to the ends of the cover and prevent spread- 110

ing thereof, each of the strips 9 being folded between its longitudinal edges to form a binder which embraces opposite sides of the ends of the cover.

5 A bail 10 is pivotally connected to the sides of the tray and is adapted to fold against an end of the tray so as to be out of the way. When the cover 7 is in position the bail is turned so that its cross piece occupies approximately a central position to engage the cover midway of its ends and hold it in place. Notches 11 are formed in the upper edges of opposite sides of the tray and receive the cross piece of the bail to prevent the same from extending above the upper edges of the side walls of the tray. Projections 12 are located upon the outer faces of the sides of the tray near the notches 11 and engage the ends of the bail 20 to hold the latter when turned to occupy a position to hold the cover in place. The extremities of the bail are bent inwardly and fit in openings formed in the sides of the tray, hence the bent ends of the bail are adapted to move outwardly when riding upon the projections 12 in either movement of the bail.

The eggs are placed in the cells of the tray, after which the cover 7 is placed in position and made secure by turning the bail to bring the ends of the cross piece in the notches 11. In this position of the bail the cross piece thereof engages the ridges of the cover and the spaces between the ridges enable the fingers of the hand to engage the cross piece of the bail so that the latter may be used as means for carrying the tray as well as a fastener for the cover. By having the bottom of textile and elevated by means 40 of the strips 2 the trays may be piled one upon the other without fear of injury to the eggs.

From the foregoing description, taken in connection with the accompanying drawing, the advantages of the construction and of the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as are within the scope of the claims appended hereto.

Having thus described the invention what is claimed as new, is:—

1. A cover consisting of a blank sheet having edge portions bent to provide a rim and having the intermediate portion formed into alternate ridges and depressions, the edge portions of the blank opposite the ridges and in line therewith being slit, overlapped and pasted, and strips pasted to the overlapped portions of the blank and extending lengthwise thereof.

2. In combination with a tray provided with a plurality of cells, a cover of sheet material for said tray embodying a plurality of ridges and depressions arranged to alternate and in parallel relation, the blank from which the cover is formed having inwardly extending cuts and the portions bordering upon the cuts being overlapped, and strips applied to the overlapped ends and serving to reinforce and strengthen the ends of the cover.

In testimony whereof I affix my signature in presence of two witnesses.

JOHN L. WEBSTER.
